UNITED STATES PATENT OFFICE

121,962

DESIGN FOR A PENDANT ELECTRIC SWITCH

George J. Meuer, Milwaukee, Wis., assignor to
Cutler-Hammer, Inc., Milwaukee, Wis., a cor-
poration of Delaware

Application June 19, 1940, Serial No. 93,105

Term of patent 14 years

To all whom it may concern:

Be it known that I, George J. Meuer, a citizen
of the United States and a resident of Milwaukee,
in the county of Milwaukee and State of Wisconsin,
have invented a new, original, and ornamental
Design for a Pendant Electric Switch, of which
the following is a specification, reference being
had to the accompanying drawing, forming part
thereof.

Figure 1 is a front elevational view of a pendant
electric switch incorporating my new design.

Figs. 2 and 3 are side and rear elevational views,
respectively, of the switch shown in Fig. 1.

Figs. 4 and 5 are top and bottom plan views,
respectively, of the switch shown in Fig. 1.

I claim:

The ornamental design for a pendant electric
switch, substantially as shown.

GEORGE J. MEUER.
